UNITED STATES PATENT OFFICE

FRANK VOREL, OF CLEVELAND, OHIO, ASSIGNOR OF ONE-HALF TO JOSEPH E. MORAVEC,
OF CLEVELAND, OHIO

INTERNAL-COMBUSTION ENGINE

Application filed February 21, 1928. Serial No. 255,940.

This invention relates to internal combustion engines and more particularly to new and useful construction in rotary valves peculiarly adapted to such engines having a plurality of cylinders and wherein the valve consists of cylindrical sections arranged in alinement within a cylindrical casing, but spaced from each other in such casing but connected by reduced axial extensions which serve to rotate the several sections in unison, though they are connected together detachably. Each of these valve sections is provided with arc-shaped channels transverse of the cylinder for suitable registration with the intake manifold and the exhaust channels, as the valve revolves, the particular arrangement of the channels being shown in this particular case as suitable for an engine of the four-cycle type, though it is to be understood that my invention is not limited to this particular type of engine.

It is an object of my invention to provide a plurality of the said arc channels in each of the valve sections, so that each section will communicate with a plurality of engine cylinders. This results in an arrangement of the valve and cylinders wherein there will be at least twice as many engine cylinders as there are rotary valve sections. Such arrangement results in a simple, efficient and quiet-running engine especially well adapted for motor vehicle work. This, as well as other objects which will be readily understood by those skilled in the art, I attain in the engine described in this specification, recited in the appended claims, and illustrated in the accompanying drawings in which—

Figure 1 is a transverse sectional view of the casing, valve and cylinder taken centrally through one of the cylinders;

Figure 2 is a front elevation of the valve and cylinders;

Figure 3 is a longitudinal vertical section of one form of valve, taken in the plane indicated by the line 3—3 of Fig. 1;

Figure 4 is a longitudinal, horizontal section of a preferred form, taken through the axis of the valve, but showing parts in elevation;

Figure 5 is a vertical section taken on the line 5—5 of Fig. 4;

Figure 6 is a side elevation of the preferred form of one of the valve sections with its axial extensions;

Figure 7 is a transverse section taken on the line 7—7 of Fig. 6;

Figure 8 is an end elevation of the section shown in Fig. 6;

Figure 9 is a vertical section of one half only of the preferred form of bearing sleeve;

Figure 10 is a cross section of one of the bearing sleeves taken on the plane indicated by the line 10—10 of Fig. 9;

Figure 11 is a horizontal section of a modified form corresponding to Fig. 4;

Figure 12 is a side view of a modified form of valve section;

Figure 13 is an end elevation of the structure in Fig. 12;

Figure 14 is a transverse section of the modified valve section taken on the line 14—14 of Fig. 12;

Figure 15 is an end elevation of one of the valve sleeves of the modified form;

Figure 16 is a side elevation of the same;

Figure 17 is a transverse section of the said sleeve taken in the plane indicated by the line 17—17 of Fig. 16;

Figure 18 is a detail view of the disc section and a portion of one of the adjacent sleeves of the modified form, with parts broken away;

Figure 19 shows elevation and section views of a collar mounted in the channel of one of the sleeves, and

Figure 20 shows elevation and section views of a spring applied to said washer.

In my improvement here illustrated, the rotary valve shaft 5 is mounted in a water-cooled casing 6 cast integrally with the cylinders 7 at one side of their upper ends, as shown in Fig. 1 of the drawings. The cylinders carry pistons 8 as shown, the particular construction of the crank shaft being more or less conventional and not disclosed in detail, the position of the same being designated in the drawings by the numeral 9.

The construction of my valve shaft and related parts, is disclosed in this case as ap-

plied to an internal combustion engine of the four cycle type and having four aligned cylinders, though it may be used in construction having more or fewer cylinders, or in engines of the two cycle type, as will later be made evident. The general arrangement of the casing 6 relative to the several cylinders is somewhat conventional, that is to say, said casing has oppositely directed apertures 10 and 11 for use in conjunction with the inlet aperture 12 of each cylinder, usually the upper one 10 connecting with the intake manifold and the lower 11 serving for the exhaust opening. The valve shaft 5 serves for suitable registration of these openings 10 and 11, respectively, with the cylinder aperture 12, as usual.

My valve shaft 5 is made up of a number of detachable sections 13, each of which comprises a cylindrical disc 14 mounted fixedly upon a reduced axial stem or shaft 15 extending in either direction from the disc, thus providing extensions for rotating the valve discs, as stated. The sections 13 are rotated together in unison by the provision on the ends of the extensions, of keys or tongues 16 and slots 17, the tongue of one extension engaging the slot of the next, as shown.

Mounted within the casing and between the discs 14 of adjacent sections 13, I provide bearing cylinders 18 which are apertured axially to receive therein the extensions of the discs. These cylinders 18 are held against rotation ordinarily by a peripheral notch or slot 19 to be engaged by a key 20 in the casing surface. While it may be possible to provide but one such cylinder 18 between adjacent discs 14, I have found it feasible and advantageous to form such bearing members in two parts 21 oppositely directed, for reasons hereinafter explained.

While rotary valves for gas engines have been used before, and such construction has been used comprising detachable sections rotating in unison, the sections have been made up of discs whose internal channels have registered directly with the intake and exhaust apertures in the casing and thereby with the respective manifolds. The bearing members or sleeves have then usually been solid, except when small longitudinal openings or channels have been provided through them for lubrication. This old construction requires therefore, as many valve discs as there are cylinders, in this type of valve.

Attention is called at this time to my own prior Patent No. 1,647,592, November 1, 1927, illustrating such construction of a sectional valve registering intermittently with the several openings in the casing to effect the proper sequence of fire. In my present improved construction of corresponding parts, I provide a sectional valve having fewer valve discs than there are engine cylinders to

be supplied. In such construction, each valve disc supplies a plurality of engine cylinders, and by the arrangement now to be described in greater detail.

I accomplish the above stated result by directing the channels in the valve discs 14 outwardly therefrom through the end faces of the discs, rather than through peripheral openings in the discs, as in the former type of which the structure of the above mentioned patent is an illustration. This feeding of gases through the end faces of the discs makes possible the serving of at least two engine cylinders by a single disc. In the form of construction shown in Figs. 4 to 8 of these drawings, each disc 14 is provided with at least two arc-shaped channels 22 and 23 which are positioned in the same plane of the disc, when but two cylinders are to be supplied thereby. Each of these channels are positioned on a common radius and open at their ends at the opposite faces of the disc at circular openings 24 positioned positively radially from the periphery of the disc, and consequently spaced from the inner wall of the casing 6.

To suitably coordinate these openings 24 with the corresponding apertures 12 leading to the several cylinders 7, the cylinders or sleeves 18 are provided with three channels 25, 26 and 27, as shown in Figs. 9 and 10, which lead to the apertures 10, 11 and 12, the inner ends of these channels registering with the openings 24 in the discs 14 in the proper order of firing for each cylinder, as the valve shaft 5 rotates. As in the usual and more common construction, the end stems 15 of the end sections of the valve are mounted for rotation in end plates 28 of the casing, the one end of the valve stem having an external sprocket 29 alining with sprocket 30 on the shaft 9, and the two sprockets geared to drive the rotary valve 5 at proper relative speed to that of the shaft 9, by the chain 32.

The cylinders 18 will therefore remain stationary with their channels 27 directed toward the cylinders 7. To enable the control of a plurality of engine cylinders from a single valve disc, the channels in the sleeves 18 are directed outward in an oblique direction relative to the vertical or transverse plane of the shaft 5, so that said channels spread outward as shown in Figs. 4, 5, 9 and 10. The cylinders 7 are, when two of them are to be supplied by a single disc 14, arranged in pairs, the respective channels 12 communicating with the cylinders 7 being directed outward toward the cylinder of the given pair and communicating with the channels 27 in the sleeves 18. A constant open passage will therefore be maintained from the inner openings 31 in the channels 27 out through the channels 12 in the casing 6 to the cylinders 7.

These sleeves 18 therefore serve the purpose of directing gases to or from a cylinder 7 from the channels 22 or 23 of the discs 14, thereby communicating with the intake and exhaust manifolds in regular order, there being as many of these sleeve members 21 as there are engine cylinders 7. The sleeves 18 serve the further purpose of bearings for the extensions 15, the inner axial apertures of the sleeves 18 being provided with an inner lining 33 in which the extensions rotate, since the sleeves 18 are stationary. The inner ends of the channels 25, 26 and 27 of the sleeves 21 have somewhat enlarged openings 34, thus resulting in an annular shoulder 35 as shown, these openings 34 registering with openings 24 in the face of the discs at different periods, the direction of communication in the channels 22 and 23 depending upon the rotary 20 position of the valve shaft in the easing. In the reference herein to the sleeves 18 and 21, the numeral 18 is merely used generically for the cylindrical members having the channels 25, 26 and 27, while the numeral 21 is 25 applied when two such sleeve parts 18 having one half the length of the latter is used.

Since the channels 25, 26 and 27 are held against rotation, and the channels 22 and 23 rotate with the discs 14, it is expedient to 30 provide the openings 34 of the sleeves with collars or bushings 36 fitted in said openings and forced against the face of the discs 14 by the annular spring elements 37 which bear directly against the shoulder 35, as shown 35 clearly in Fig. 4. This latter construction tends to avoid leakage at the points of connection between the channels in the sleeve and the channels 22 and 23 of the discs. If the shorter sleeves 21 are used, as shown in 40 these drawings, usually the shorter lining sleeves 33 will be used, as shown in Fig. 9.

It is to be noted that in the form of discs 14 shown in Figs. 4 to 8, the channels 22 and 23 may lie in the same transverse plane, since 45 there is no communication whatever between them in the same disc. It is also evident that there is sufficient space in a single disc to permit arrangement of more than two such arc-shaped channels 22 and 23, even in the same 50 transverse plan of the disc.

I have disclosed in this application structure for supplying a plurality of engine cylinders from a modified form of valve disc of the general form as that shown in Fig. 3 55 of the drawings. Here is shown generally, discs 44 which are provided with arc-shaped channels 42 and 43 for causing proper communication of the engine channels 12 with the several manifolds, and which will now be 60 explained more in detail. Since in Figs. 11 to 14 and 18, the modified form of disc 44 is shown much longer axially so that the said channels 42 and 43 are in separated transverse planes, the position of the several openings 65 24 in the faces of these discs will be

more nearly positioned directly under the cylinders which they finally supply, so that the channels in the modified sleeves for intermediate communication between the discs and engine cylinders, will not be of the decidedly oblique type, but will more nearly approach the L-type as illustrated in Figs. 11 and 18.

In the latter views the L channels 45, 46 and 47 communicate at their inner ends with the openings 24 in the discs in the same manner as such connection was made in the preferred form of Figs. 4 to 10. The same use is made of the bushing and spring 36 and 37 positioned against the shoulder 35 also as in the preferred form. The engine channels referred to as part 12 in the preferred form, are only slightly changed in their inclination as to the axis of the valve shaft, so that they may communicate with the several channels 47 in the discs 44. Otherwise, the form of construction shown in Figs. 3, 11 and 18 is much the same as that shown in Figs. 4 and 5.

It is peculiarly characteristic of the discs 44, that the channels 42 and 43 lie in different transverse planes, resulting in the modification of the channels in the sleeves 51 to accommodate the modified connection between the disc channels and the openings 52 to the upper part of the engine cylinders. In either form, the stationary sleeves have the same radius as the rotating discs. Also, in both forms the sleeves are provided with channels in a radial plane communicating with openings in the periphery and openings in the end face, so that gases entering either opening will be directed to the other. Both forms of discs, however, have imperforate peripheries and spaced openings at either end, the openings of each end being connected by internal 100 and arc-shaped channels, as before described.

In both forms, the casing 6 is integral with the aligned engine cylinders, and is provided with three sets of apertures, each set being in alignment and comprising as many apertures 110 as there are engine cylinders. My construction therefore embodies a useful and highly efficient improvement in means for effecting accurate communication between the several cylinders and the apertures in the casing leading to the intake and exhaust manifolds. It will be apparent, that in each form, as the discs revolve, communication is effected between the intake aperture and the corresponding cylinder through one of the channels in 120 the disc, when the latter is in a particular position of rotation, while at the same time, another channel of the same disc will effect communication between the exhaust manifold and another engine cylinder, the same disc thus serving to supply a plurality of cylinders.

The particular construction used for external connection with the manifold and exhaust apertures of the casing forms no part 130

of the present invention, and is not shown or described in detail. It will be apparent from this disclosure that the rotating discs of my improved valve will ordinarily be positioned on a plane intermediate the engine cylinders of a pair, so that the disc may readily supply both cylinders. If however, it is desirable to supply a greater number than two cylinders with a single disc, the latter will be 10 positioned in a plane about midway the length of the set of cylinders to be so supplied. In any case, sleeves will be provided having at least one channel connecting with each engine cylinder.

15 Having thus described my invention, what I claim as new and desire to secure by Letters Patent is:

1. In a multi-cylinder gas engine of the rotary valve type, a common valve casing adjacent the engine cylinders, in combination with a composite valve of alined sections in the bore of the casing, each section comprising a disc for supplying a set of engine cylinders, and means mounted in said bore between the discs for affording communication between the discs and the several engine cylinders.

2. In a multi-cylinder gas engine of the rotary valve type, a common valve casing adjacent the engine cylinders, in combination with a composite valve of alined sections in the bore of the casing, comprising a disc in each section for supplying a set of engine cylinders, each disc having channels therein directed toward the axial ends of the discs, and means mounted in said bore between the discs for affording communication between the said channels and the several engine cylinders.

3. In a sectional rotary valve shaft for internal combustion engines, a series of alined and spaced discs having imperforate peripheries but axial openings on their end faces connected with internal channels effecting communication between said openings.

4. In a sectional rotary valve shaft for internal combustion engines, a series of alined and spaced, cylindrical discs having imperforate peripheries and a plurality of axial openings on each of their end faces connected with independent internal channels each communicating with the openings in but one end of a disc.

5. In a sectional, rotary valve shaft for internal combustion engines, a series of spaced discs having imperforate peripheries, but axial openings on their end faces connected with arc-shaped, internal channels for directing gases therethrough in an arc from one opening to another.

6. In a multi-cylinder gas engine of the rotary valve type, a composite sectional valve comprising spaced sections in axial alinement and each section supplying a plurality of engine cylinders, and a pair of spaced bearing

sleeves in stationary position about each of said sections, the latter being mounted for rotation in said sleeves and having channels connecting the several valve sections with certain of said engine cylinders.

7. In a multi-cylinder gas engine of the rotary valve type, a composite sectional valve comprising spaced sections in axial alinement, each section having a plurality of independent internal channels for supplying a plurality of engine cylinders, and a pair of spaced, stationary bearing sleeves enclosing each of said sections, the latter being mounted for rotation in said sleeves, and the sleeves having channels connecting the several section channels with corresponding engine cylinders.

8. In a sectional rotary valve shaft for internal combustion engines, a cylindrical disc in each section having an imperforate periphery and arc-shaped internal channels spaced from each other, but directed toward opposite ends of the disc, there being openings on its end faces communicating with the ends of the several channels.

9. In a sectional rotary valve shaft for internal combustion engines, each section including a cylindrical valve disc having an imperforate periphery and a plurality of arc-shaped and independent channels therein positioned in a common transverse plane, but directed toward opposite ends of the disc, there being axial openings on the end faces of each disc communicating with the ends of the respective channels for directing gases in an arc from one opening to another.

10. In a sectional rotary valve shaft for internal combustion engines, each section comprising a cylindrical disc and axial extensions of reduced diameter, said extensions of adjacent sections having detachable connection to cause rotation of all sections together, and cylindrical sleeves having axial openings for receiving the said extensions therein and transverse channels connecting openings in their periphery with openings in one of the end faces, there being as many sleeves as there are engine cylinders.

11. A valve shaft comprising longitudinal valve sections, each section comprising a rotary disc having internal channels opening outward at the axial faces thereof, and reduced axial extensions, stationary bearing sleeves enclosing said extensions and having transverse channels therein whose outer ends have openings at the periphery and the inner ends having openings in the axial faces of said sleeves, and which register intermittently with the disc channels as the sections rotate, there being one more of said transverse channels in each sleeve than there are openings in either end of the adjacent disc.

12. In a multi-cylinder gas engine of the single, rotary valve type, a common valve casing communicating with the cylinders, in

combination with a composite sectional valve in the bore of the casing comprising spaced discs alined axially in said bore and having means for causing all the sections to rotate together, bearing sleeves having the same diameter as the discs and positioned between the latter in the bore, the sleeves having peripheral and face openings and connecting internal channels, and the discs having imperforate peripheries and face openings, and arc-shaped channels therein connected with their respective face openings, so that the disc openings will register with the face openings of the sleeves intermittently.

15 In testimony whereof, I have hereunto subscribed my name this 30th day of January, A. D. 1928.

FRANK VOREL.
